(57) CLAIM

The ornamental design for a medication container shredding machine, as shown and described.

DESCRIPTION

FIG. 1 is a front perspective view of a medication container shredding machine showing my new design.

FIG. 2 is a top view thereof.

FIG. 3 is a front view thereof.

FIG. 4 is a right side view thereof.

FIG. 5 is a rear view thereof.

FIG. 6 is a left side view thereof; and,

FIG. 7 is a bottom view thereof.

The broken lines which define the bounds of the claimed design in FIG. 7 form no part thereof.
